(57) **CLAIM**

The ornamental design for a bottle, as shown and described.

DESCRIPTION

FIG. 1 is an elevational view of a bottle showing our new design;

FIG. 2 is another elevational view rotated about 60° to the left as compared to FIG. 1;

FIG. 3 is a top plan view thereof; and,

FIG. 4 is bottom view thereof.

The dot-dash-dot lines shown in FIGS. 1 and 2 represent boundaries of the claimed design. The broken lines shown in FIGS. 1-3 are for illustrative purposes only and form no part of the claimed design.
